UNITED STATES PATENT OFFICE.

HENRY TILL, OF LOS ANGELES, CALIFORNIA.

CAN-OPENER.

1,110,728.

Specification of Letters Patent. Patented Sept. 15, 1914.

Application filed January 2, 1913. Serial No. 739,921.

To all whom it may concern:

Be it known that I, HENRY TILL, citizen of the United States, residing at Los Angeles, in the county of Los Angeles and 5 State of California, have invented certain new and useful Improvements in Can-Openers, of which the following is a specification.

This invention relates to improvements in attached can opening devices, and is designed primarily for use in conjunction with the ordinary type of condensed milk and cream cans. In opening such cans, it is customary to punch two holes in the top of the can by the use of a nail, ice pick, or some 10 other sharp pointed instrument. Not only is this method inconvenient but the contents of the can are liable to become contaminated by dirt upon the instrument used. Aside from this it is no easy matter to seal the 15 openings after a portion of the contents have been poured from the can when the latter is to be put away for future use, for the openings are not of a size to receive a bottle cork, nor are they as a usual thing regular.

20 The present invention contemplates the provision of an attached opening device for cans, which device will normally assume such a position as to permit of the cans to which it is applied being stacked one upon 25 another and side by side and which may be manufactured and applied to the can at an extremely low cost.

The invention also aims to provide an 30 opening device which may be readily and quickly manipulated so as to punch openings in the top of the can to which it is applied and which may be subsequently employed as a means for sealing or closing 35 these openings so as to prevent the entrance 40 of dust and dirt into the can and to prevent clogging of the openings.

The present invention is designed more 45 particularly as an improvement on the structure shown in my co-pending application, filed Oct. 10, 1912, Serial No. 725,096. In the form of the opener shown in the co-pending application, the pointed ends of the strips upon the can top project beyond the edge of the top, but in this position they are 50 somewhat liable to be struck by other cans and broken or bent, and the present invention therefore contemplates housing the piercing points of the device in a recess in the top of the can.

55 Another feature of the invention resides in the formation of a novel finger-hold upon

the point-carrying strips, whereby the strips may be sprung upwardly and swung upon their pivot. Also, the present invention contemplates a novel pivotal mounting for 60 the strips.

For a full understanding of the invention reference is to be had to the following description and accompanying drawing, in which:—

65 Figure 1 is a perspective view illustrating the invention applied to the top of a can and illustrating the strips in position prior to manipulation to pierce the can top. Fig. 2 is a top plan view illustrating in full lines 70 the normal position assumed by the strips and in dotted lines the position assumed in Fig. 1. Fig. 3 is a vertical transverse sectional view, the strips being in the position shown in Fig. 1. Fig. 4 is a top plan view 75 illustrating a slightly modified form of the invention. Fig. 5 is a view illustrating the manner in which the top of the can is pierced by the device embodying the invention. Fig. 6 is a perspective view of the 80 point-carrying end of one of the strips. Fig. 7 is a plan view of a portion of the blank from which one of the piercing members is formed, the blank being in its initial folded position.

85 Corresponding and like parts are referred to in the following description and indicated in all the views of the accompanying drawings by the same reference characters.

90 In the drawings, the numeral 1 indicates the top of a can, for example, a can containing condensed milk. In removing the contents of such a can it is customary to punch two holes in the top at diametrically opposite points so that the contents may 95 flow from the can at one of the openings as air enters the can through the other, and as before stated, the opening device embodying the present invention is designed to be manipulated to punch the can top, and is arranged upon the said top. The opening device includes two pivoted members each in the nature of a strip 2 of sheet metal and these strips are pivoted at their inner ends upon the top of the can and carry at their 100 outer ends the piercing points heretofore referred to. In pivotally mounting the strips upon the top of the can, the said top, preferably at its center, is struck up, as clearly shown in dotted lines and indicated 105 at 3 in Fig. 3 of the drawings, to form a hollow stud to which the inner ends of the 110

strips 2 are fitted in the manner shown in the said figure. After the strips have been assembled with the stud, the stud is upset to form a head 4 which serves to prevent disengagement of the strips 2. As stated above, each of the strips carries piercing points and these points are indicated in the drawings by the numeral 5 and as illustrated are conical in form. In forming the points 5, the strip 2 is folded upon itself adjacent one end as at 6 and beyond its fold is cut to substantially V-form as at 7 and slit inwardly from corresponding points at its opposite edges as indicated at 8. The V-shaped portion of the strip is bent up substantially in a line with the slits, and is finally formed to the shape shown in Fig. 6.

In forming up the can top 1, the material thereof is struck down as indicated at 9 whereby to form a housing for the points 5, the manner of housing the points within the recess 9 being clearly illustrated in Figs. 1 and 2 of the drawings. If desired, two recesses 10 may be formed in the top of the can in place of the single recess 9 so that each point will be independently housed. It will be understood, of course, that the strips are of a length less than the radius of the circle described by the edge of the can top 30 so that their outer ends will terminate short of the said edge. For convenience in springing the strips upwardly to move the piercing points 5 out of the recesses 9 or 10 in which they are normally housed and also to withdraw the piercing points from the openings punched in the can top each strip 2 has its side edge portions near its outer end struck up as at 11 whereby to form oppositely located finger holds beneath which the nails 40 of the thumb and forefinger may be engaged for the purpose stated.

In using the device, the strips being in the position shown in Fig. 2 of the drawings, are lifted or sprung upwardly so as to disengage the piercing points from the recess 9 and the strips are then swung upon their pivots so as to assume substantially the dotted line position shown in the said figure.

Downward pressure is then exerted against the ends of the strips or the can may be inverted and downward pressure exerted upon it so as to cause the piercing points to enter or pierce the top 1, as shown in Fig. 5. The strips are then again swung upwardly and swung around to normal position, leaving both openings exposed. The contents of the can may then be readily poured and when the desired quantity has been removed, the strips are again swung back to the dotted line position shown in Fig. 2 and their piercing points 5 are inserted into the openings pierced in the can top and indicated in Fig. 5 by the numeral 12. Thus, the piercing points serve as closures for the openings 12 as well as a means for producing these openings and consequently the contents of the can may be kept fresh and clean and the formation of the usual film at the openings 12 is prevented.

It will of course be readily understood that whereas the strips are here shown as pivoted substantially at the center of the can top, the pivot may be located eccentrically if desired and as shown in my before mentioned co-pending application. In other words the location of the pivot is immaterial so long as the essential features of the invention are in evidence.

Having thus described the invention what is claimed as new is:-

The combination with a container having a sealing top struck inwardly to provide a recess or seat and outwardly to provide a hollow stud spaced from the seat, of a resilient member perforated at one end to engage over the stud, the stud being headed to pivotally secure said member in place, and a piercing point carried by the free end of the resilient member and adapted to normally seat in the recess.

In testimony whereof I affix my signature in presence of two witnesses.

HENRY TILL. [L. s.]
